UNITED STATES PATENT OFFICE.

CHARLES G. CHENEY, OF TACOMA, WASHINGTON.

DEVICE FOR LOCATING AND RAISING SUNKEN VESSELS.

1,269,523.

Specification of Letters Patent. Patented June 11, 1918.

Application filed March 19, 1917. Serial No. 155,672.

To all whom it may concern:

Be it known that I, CHARLES G. CHENEY, a citizen of the United States, residing at Tacoma, in the county of Pierce, State of Washington, have invented certain new and useful Improvements in Devices for Locating and Raising Sunken Vessels, of which the following is a specification.

This invention relates to devices for recovering wrecked vessels and has for its objects to provide means whereby the submerged wreck may be located, and whereby a suitable raising means may be guided to said wreck. The invention further has for its object to provide a suitable raising means adapted to be guided by said locating means, and a suitable device fixedly mounted on the vessel and adapted to be engaged by said raising means and adapted to secure it to said vessel.

Further objects are to provide means whereby the lifting strains on the ship are carried directly by its keel system and whereby, if the ship is lying on its side, the strains for righting it are carried by the vessel framing.

I attain these and other objects by the devices, mechanisms and arrangements illustrated in the accompanying drawings, in which

Figure 1 is a vertical longitudinal section of a ship equipped with my invention;

Fig. 2 is a transverse section thereof;

Fig. 3 is a perspective view of one of the loops secured to the ship;

Fig. 4 is a vertical section of the hook, or raising means, showing it in engagement with the loop, or securing means;

Fig. 5 is a similar view of said parts taken in a plane at right-angles to that of Fig. 4; and Fig. 6 is a diagrammatic view of the submerged vessel, lying on its side, and showing one locating means still floating while another has been disconnected from the floating buoy and is guiding the raising means to the securing means thereon.

Similar numerals of reference refer to similar parts throughout the several views.

The vessel 1 is provided with the usual longitudinal interior keel 2 to which the frames 3 of the ship are secured, the skin 4 being secured to the frames 3. The deck 5 is supported by suitable transverse beams 6.

On top of the deck 5 I fasten one or more heavy securing loops 7, by means of four strong bars 8 which extend downward there-

from, through the ship, and are secured at their lower ends to the two sides of the interior keel 2. These bars 8 carry the strain to the keel 2 when the ship 1 is supported by the said securing loops 7, as hereinafter described. The bars 8 are also secured to a pair of the transverse beams 6 so that when the submerged ship lies on its side and a lifting strain is applied to the loops 7, to right it, the said strain will be transferred by the beams 6 to the frames 3 of the ship, thus relieving the major portion of the bars 8 from any bending action.

A cable-holder 9 is permanently and fixedly fastened to the deck 5 of the vessel near each such securing loop 7. This holder 9 is capable of retaining a long light cable 10 which is wound thereon in such a way that it may be readily unwound from the top, or free end, and so that the lower end passes to the said securing loop 7, to which said end is loosely attached. The upper end of the cable 10 is secured to the bottom of a buoy 11, of sufficient size to float when said cable 10 is unwound and is hanging therefrom. The buoy 11 may also be large enough to support one of the hereinafter described raising hooks. This buoy 11 is preferably loosely mounted on the cable-holder 9, as shown, so as to be free to rise therefrom when the ship sinks. As the vessel 1 sinks the cables 10 unwind from the holders 9 until the vessel strikes the bottom, and the buoys 11 float on the surface to indicate the position of the ship.

When it is desired to recover the sunken ship, the double snap hooks 12 are lowered thereto and engage the securing loops 7 as follows: Each such hook 12 is secured to the end of a heavy cable or chain 13, carried by the raising ship 14. The hook 12 consists of an inverted U-shaped body, each depending arm of which is forked to receive and hold a latch member 15 which is mounted on a pin 16 so as to be free to swing thereon in a vertical plane. The two said latch members 15 are each shaped so as to extend one-half way across the space between the arms of the hook 12 and rest against each other, or to swing upward therefrom so as to allow the loop 7 to pass upward from below into the space above the said latch members 15. But the said latch members 15 cannot swing farther down than said central position.

A web 17 extends across the space above

the latch members 15 from arm to arm of the hook and is adapted to strengthen the said arms. This web 17 is provided with a guide hole 18 through which the light cable 10 5 may be threaded, and by which the whole hook is guided to the loop 7.

My apparatus operates in the following manner:—

When a vessel, equipped with my invention, sinks, all the buoys 11 (and they may be many) break away therefrom and float on the surface, thus unwinding the cables 10 from the holders 9 as the vessel goes down. These buoys 11 thus form a marker 15 for the location of the wreck and also serve for a means of rescuing those persons thrown into the water from the sinking vessel. Then, when the recovering vessel 14 arrives, one of the buoys 11 is raised from the water 20 (Fig. 6) and is detached from the cable 10, which is then threaded through the guide hole 18 in the web 17 of one of the hooks 12, which has previously been secured to a heavy cable or chain 13, and the free end 25 of the light cable 10 is made fast on the vessel 14. Then the cable 13 is slackened to lower the hook 12 and the hook slides down the cable 10, which may be made as taut as desired, until it reaches the loop 7 secured 30 to the sunken ship 1. The loop 7 forces the latch members 15 to turn on the pins 16 to allow it to pass above the said latch members 15, when they swing down again and close the hook so that the loop 7 cannot now 35 pass therefrom. Then the other buoys 11 are each similarly removed and hooks slid down their respective cables 10 to their respective loops 7 on the sunken ship, until a sufficient number have been thus attached to raise the ship. Any of the well known devices 40 may be used in the actual raising of the ship, as may be desired or as circumstances may permit.

Having described my invention what I 45 claim is:

1. In a device of the class described, the combination with a vessel having a frame including an inner keel member and transverse deck beams, of securing means mounted 50 on the deck of the vessel, vertical tension bars or members fitted against the sides of the keel member and the transverse beams

and secured to the said securing means, and raising mechanism having means for engaging the securing means. 55

2. In a device of the class described, the combination with a vessel having a frame including an inner keel member and transverse deck beams, of securing means mounted on the deck of the vessel, vertical tension bars or 60 members arranged in pairs at opposite sides of the keel member and fitted against the same and the transverse beams, said tension bars or members being secured to the keel member and to the beams and connected with the said securing means and raising mechanism having means for engaging the securing 65 means.

3. In a device of the class described, the combination with a vessel having a frame 70 including an inner keel member and transverse deck beams, of securing means consisting of a plate arranged upon the deck of the vessel and provided with an upwardly projecting loop, vertical tension bars or 75 members located at the corners of the plate and connected with the same, said tension bars or members being fitted against the keel member and the transverse beams and secured to the same, and raising mechanism 80 having means for engaging the said loop.

4. In a device of the class described, the combination with a loop and means for securing the same to the deck of a vessel, of raising mechanism including an inverted 85 open ended approximately U-shaped body and a pair of pivoted latch members mounted on the body at opposite sides thereof and arranged to close the open end of the said body and engage the said loop. 90

5. In a device of the class described, the combination with a loop, and means for securing the same to the deck of a vessel, of a line connected with the loop and raising mechanism including a body provided with 95 an opening through which passes the said line, said body being provided with an open end adapted to fit over the said loop and a pair of latch members pivotally mounted on the body at opposite sides thereof and arranged to close the open end of the body 100 and engage the said loop.

CHARLES G. CHENEY.
